A. WEMYSS.
Heating-Stoves.

No. 7,497.

Patented June 16, 1874.

Witnessed and signed

UNITED STATES PATENT OFFICE.

ALEXANDER WEMYSS, OF PHILADELPHIA, ASSIGNOR TO SEYMOUR RAYMOND AND JOSEPH CAMPBELL, OF MIDDLETOWN, PENNSYLVANIA.

DESIGN FOR HEATING-STOVE.

Specification forming part of Design No. **7,497**, dated June 16, 1874; application filed June 5, 1874.
[Term of Patent 7 years.]

To all whom it may concern:

Be it known that I, ALEXANDER WEMYSS, of Philadelphia, Pennsylvania, have produced or invented a Design for a Heating-Stove, of which the following is a specification:

My design for a heating-stove is clearly illustrated by the figure in the accompanying drawing.

The top A of the stove is of the general shape shown, is ornamented, both above and below, by annular rows of beading, and is surmounted by an urn, B. The cylindrical portion D of the body of the stove, between the top A and casing E, is ornamented by vertical rows of beading, which produce the effect of vertical panels, and the upper portion of the casing E has three-light mica windows a, of the shape represented, each provided with a scroll-like ornament at the top, while the under portion of the said casing E is also ornamented, as shown. The portion F of the stove-casing

above the base G has two-light mica windows b, and is, together with the said base and feet d of the stove, ornamented in a manner so clearly shown by the drawing as to render minute description unnecessary.

I claim—

The design for a heating-stove having an ornamental top, A, surmounted by an urn, B, a paneled body, D, casings E and F, with mica windows a and b, and an ornamented base, G, and feet d, all as described, and as represented in and by the accompanying drawing.

In testimony whereof I have signed my name to this specification in the presence of two subscribing witnesses.

ALEXANDER WEMYSS.
